(57) **CLAIM**

The ornamental design for a cell phone case with resilient suspension hook, as shown and described.

DESCRIPTION

FIG. 1 is an upper isometric rear view of a cell phone case with resilient suspension hook according to the present design with the suspension hook in the open position; FIG. 2 is an upper isometric rear view of the cell phone case with resilient suspension hook according to the present design with the suspension hook in the closed position; FIG. 3 is an upper isometric front view of the cell phone case with resilient suspension hook according to the present design;

FIG. 4 is a front view of the cell phone with resilient suspension hook;

FIG. 5 is a rear view of the cell phone case with resilient suspension hook according to the present design;

FIG. 6 is a right side view thereof as shown in FIG. 2;

FIG. 7 is a left side view thereof as shown in FIG. 2;

FIG. 8 is a bottom view thereof as shown in FIG. 2; and,

FIG. 9 is a top view thereof as shown in FIG. 2.

1 Claim, 8 Drawing Sheets
